(57) **CLAIM**

The ornamental design for a flared lid closure, as shown and described.

DESCRIPTION

FIG. 1 is an upper right front corner isometric view of a flared lid closure showing our new design;

FIG. 2 is another isometric view thereof rotated about 180° from the view shown in FIG. 1;

FIG. 3 is a top plan view thereof;

FIG. 4 is a front elevational view thereof;

FIG. 5 is a right side elevational view thereof, the left side elevational view thereof being a mirror image; and,

FIG. 6 is a rear elevational view thereof.

In the drawings, the broken lines depict environmental subject matter only and form no part of the claimed design.
